Attorney

UNITED STATES PATENT OFFICE.

PATRICK J. WALSH, OF MORRIS, ILLINOIS.

PAN.

Application filed October 3, 1925. Serial No. 60,365.

The present invention relates to a water pan for a radiator.

The principal object of the invention is to provide a pan of this nature which may be supported above the radiator so that water therein will be evaporated to humidify the air rising from the radiator.

The pan is particularly adapted for use in the attachment disclosed in my companion application (Case B) Serial No. 60,364, filed October 3, 1925, and is also particularly adapted for being supported on the bracket shown in my application (Case A) filed in the Patent Office on September 9th, 1925, and bearing Serial No. 55,278.

The present application is referred to as Case C in my companion application, Case B.

In the drawings—
20 Figure 1 is a front elevation of the pan embodying the features of my invention.

Fig. 2 is a top plan view thereof, and

Fig. 3 is a transverse vertical section taken therethrough substantially on the line 3—3 25 of Fig. 2 looking in the direction of the arrow.

Referring to the drawing in detail, it will be seen that the pan includes the ends D and the pan proper or body F. Each end D is provided with a side 5, a top 6, a side 7 longer than the side 5, and merging into an inclined upright 8 which in turn merges into a bottom 9 having the depending rectangularly disposed flange terminals 10. The sides 7 are disposed outermost. These ends D are adapted to rest on the brackets B as is apparent. The pan proper or the body thereof includes a bottom 11, end walls 12 which are soldered, welded or otherwise permanently attached to the sides 5, a rear wall 13 of the same height as the end walls 12, and a front wall 14 less in height than the walls 12 and provided on its upper edge with an inwardly disposed rectangularly extending flange 15. The pan proper is

adapted to receive water which will be evaporated by the heat rising from the radiator.

The flange 15 tends to deflect the evaporation forwardly out into the room. The ends D rise above the upper edges of the 50 walls 12 and 13 and if desired, a shelf, board, or the like may be supported on the tops 6 longitudinally above the body F. Of course, it is obvious, that the pan is more particularly designed for use in the combination 55 shown in my companion application (Case B).

The pan is capable of being manufactured at a very small cost because of its simple construction, and when used with other devices, will prove attractive in its appearance. The pan is also strong, durable and the present embodiment thereof has attained in actual practice features of advantage as 60 enumerated above.

It is apparent that changes in the details of construction, in the sizes in the materials, and in the combination and arrangement of parts may be resorted to without departing from the spirit or scope of the invention as 70 hereinafter claimed or sacrificing any of its advantages.

Having thus described my invention, what I claim as new is:—

A device of the class described including 75 a pan, end supporting members for said pan each formed from a single sheet of metal bent to provide a side attached to the adjacent end of the pan and merging at its upper end into an outwardly rectangular disposed 80 top, said top merging into a depending rectangularly disposed side longer than the first mentioned, side, said second side merging into an inwardly inclined upright, said upright merging into a bottom parallel to the 85 top and fixed to the lower end of the first side and terminating in a depending flange.

In testimony whereof I affix my signature.

PATRICK J. WALSH.
